UNITED STATES PATENT OFFICE.

ERNST KARL ROTHE, OF EISENACH, GERMANY.

FIELD-GUN.

SPECIFICATION forming part of Letters Patent No. 736,881, dated August 18, 1903.

Original application filed February 3, 1903, Serial No. 141,709. Divided and this application filed May 4, 1903. Serial No. 155,649. (No model.)

To all whom it may concern:

Be it known that I, ERNST KARL ROTHE, a subject of the Grand Duke of Saxe-Weimar, residing at Eisenach, in the Grand Duchy of Saxe-Weimar, German Empire, have invented certain new and useful Improvements in Field-Guns, of which the following is a specification.

This invention relates to certain new and useful improvements in or relating to field-guns and is what may be termed a "brake-protector."

The subject-matter of this application is a division of my application for Letters Patent, Serial No. 141,709, filed February 3, 1903.

The main desideratum in the support for field-guns is that it should be as light as possible and yet be constructed in such a manner that the parts regulating the recoil and the brake-cylinder, with its stuffing-box, spring, piston, and piston-rod, should be sufficiently protected on all sides against foreign bodies and splinters of shells. This is effected in accordance with my invention by providing the upper carrier or support on its under side with a protective armor hinged to the upper carriage. The upper carriage and the said armor are separated by a free space from the brake-cylinder, so that the latter is protected by the armor against splinters of shells that may come from the outside or from below, and the armor is so connected to the carrier that it can be lowered, so as to allow of easy access to the brake, and more particularly to the stuffing-box.

In describing the invention in detail reference is had to the accompanying drawings, forming a part of this specification, wherein like reference characters denote corresponding parts throughout both views, and in which—

Figure 1 is a side elevation of the brake-protector broken away at one end and set up in position; and Fig. 2 denotes a section on line A B, Fig. 1.

Referring to the drawings by reference characters, *o* denotes the upper carrier, which is so arranged in relation to the brake as to

form an intervening space between the same. The reference character *u* denotes the armor, which closes the intervening space at the bottom thereof and also forms a clearance-space between the said armor and the brake. The armor-plate *u* is hinged to the upper carrier, as at *z*, and its free end is connected to the carrier *o* by means of the pins *z'* passing through the eyes *z²* *z'*.

The construction of brake-protector set forth enables the entire brake-gear—that is to say, the brake-cylinder, with stuffing-box, piston-rod, and drawing-spring—to be protected against foreign bodies and splinters of shells, which could otherwise get into it from the outside, as well as from below, and at the same time enables the armor-plate *u* to be disconnected from the upper carrier *o* to enable the inspection of the brake-cylinder, access to the stuffing-box, and the cleaning thereof.

Having now particularly described and ascertained the nature of my said invention and in what manner the same is to be performed, I declare that what I claim is—

1. In a field-gun carriage, a slide-frame pivoted to the main carriage, consisting of vertical plates along the top edge of which the gun recoils, a recoil-check and recuperator means placed between said plates, an armor-plate hinged at one side to one of said plates, and means for connecting the other side of the armor-plate to the other of said plates.

2. In a field-gun carriage, a slide-frame pivoted to the main carriage, consisting of vertical plates along the top edge of which the gun recoils, a recoil-check and recuperator means placed between said plates, an armor-plate hinged at one side to one of said plates, and eyes and pins for connecting the other side of the armor-plate to the other of said plates.

In testimony whereof I have hereunto set my hand in presence of two subscribing witnesses.

ERNST KARL ROTHE.
